UNITED STATES PATENT OFFICE.

DANIEL A. McDONEL, OF DETROIT, MICHIGAN, ASSIGNOR TO THE PENINSULAR BROOM COMPANY, OF SAME PLACE.

BROOM.

SPECIFICATION forming part of Letters Patent No. 531,056, dated December 18, 1894.

Application filed May 15, 1894. Serial No. 511,355. (No model.)

To all whom it may concern:

Be it known that I, DANIEL A. McDONEL, a citizen of the United States, residing at Detroit, in the county of Wayne and State of Michigan, have invented certain new and useful Improvements in Brooms, of which the following is a specification, reference being had therein to the accompanying drawings.

The invention consists in the novel method 10 of manufacturing brooms, and the method consists in the steps employed in forming the body of the broom, and further in the steps employed in securing the covering and body corn to the handle and in applying the covering to the body, as more fully hereinafter described.

In the drawings, Figure 1 is an end elevation of the clamping machine in which the body is formed and showing the frame in position. Fig. 2 is a view of the receiving block of the clamp, as shown in Fig. 1, the corn and handle being in position. Fig. 3 is a similar view showing the corn compressed ready to receive the frame, the ends of the frame bent 25 to form hooks to engage over the handle. Fig. 4 is a cross-section on line $x-x$, Fig. 3. Fig. 5 is a plan showing the broom with the body and covering secured thereto. Fig. 6 is a cross section through Fig. 5 taken at the 30 bridle or frame. Fig. 7 shows the covering turned over the body and Fig. 8 shows the finished article.

In the present state of the art it is necessary to use skilled labor at all steps—first to bind the corn to the handle while revolving, 35 by a binding wire, next to form the shoulders on the body to give the desired shape and finally to apply the covering and sew the broom.

40 In manufacturing the broom I employ a clamping machine as shown in Fig. 1 comprising the base A, the stationary recessed jaw B and the movable jaw C having suitable actuating devices. The jaw C is composed of 45 two separated bars a , as shown in Fig. 4. In the sides of the stationary jaw B are guide slots b .

D is a metallic bar, rod or strip bent into U shape, or into the shape of a staple and of 50 a size between the legs thereof equal to the

desired width of the broom. The staple or frame D thus formed I engage into the guide ways in the stationary jaw of the clamping machine and in this frame I place the butted ends of the corn, from which a broom is to be 55 manufactured. I next insert the butt end of the handle E into the corn as near the center thereof as possible. I then form on the ends of the frame the hooks or bends F.

The movable jaw C of the clamp is provided with a central notch G. The movable jaw of the clamp is then brought over the corn in the stationary jaw and power applied to compress the corn as shown in Fig. 3. The ends of the frame are then bent down over 65 the corn with the hooks engaging over the handle, as shown in Fig. 6, and power is applied to the frame between the bars a of the clamp to press it tightly upon the compressed corn in the clamp. This I preferably do by 70 employing a hammer or die, striking hard upon the frame to give it the desired shape. I next drive suitable staples c into the handle over the ends of the frame, thus holding them in proper relation to the handle. The body 75 of the broom is then released from the clamp and the opposite side is treated in the same manner. This will produce a rigid frame or bridle secured to the handle and tightly clamp the corn thereto, besides giving it the desired 80 shape, the cross-section thereof being substantially as shown in Fig. 6.

The ends of the body corn are evened before securing them by the frame to the handle. The covering may now be applied to the 85 frame in any desired manner to produce the finished article shown in Fig. 8.

The covering is shown at G', Figs. 4 and 5, with the parts extending upwardly parallel with the handles. It is applied to the handles either before or after the body is secured as may be found expedient. When the cover and body have been properly secured the former is turned over the latter, as shown in Fig. 7, and then properly secured in place on the 95 handle by means of a ferrule as shown at H in Fig. 7 and firmly secured or in any other suitable manner.

It will be observed in forming the body I first compress the corn in an open frame, then 100

form the frame around the corn and handle, clamping it thereon and finally securing the covering over the body. This I consider broadly to be my invention.

5 What I claim as my invention is—

1. The herein described method of manufacturing brooms which consists in first compressing the corn around the end of the handle, in an open metallic frame, next in forming the frame around the butts of the compressed corn to clamp the corn in the frame, securing the frame to the handle, and finally applying the cover upon the body, substantially as described.

15 2. The herein described method of manufacturing brooms which consists in first com-

pressing the corn around the end of the handle in an open frame, next in forming the frame around the butts of the compressed corn to clamp the corn in the frame, securing the frame to the handle, securing the cover to the handle above the body with the points extending upward, and finally turning the cover over the body and securing the same thereto, substantially as described. ²⁵

In testimony whereof I affix my signature in presence of two witnesses.

DANIEL A. McDONEL.
